UNITED STATES PATENT OFFICE

BURT S. HARRISON, OF BROOKLYN, NEW YORK

LUMBER DRIER

Application filed April 15, 1929. Serial No. 355,121.

My invention relates to improvements in lumber driers and more particularly to driers of what is known as the platen type in which banks of heated platens are used to carry the stock which may be lumber, veneer, dimension stuff or analogous material.

In driers of this type the platens open to receive the stock and then are closed against it so that the stock will be held flat in order that it may not warp or twist during the drying process. In moving the platens it is the prevailing custom to practically lift the load in closing or opening them and this renders it necessary to use rather ponderous, cumbrous structures and requires a good deal of power. It follows that such apparatus is slow in operation.

The object of my invention is to improve structures of this character and obviate the difficulties referred to and other difficulties to the end that the structure may be simplified, its operation rendered more convenient and less expensive and that the time for loading and handling may be cut down.

My invention is also intended to produce a structure of better efficiency than those heretofore used for the purpose specified and in which the customary or preferred arrangements for automatically regulating temperature, circulation, humidity and the like can be used as desired.

In carrying out this idea I employ a series of tilting grids which operate as a unit and in which the platens are carried by the grids in such a way that the tilting of the grids regulates the distance between the platens so that, for example, if the grids are vertical the platens will be separated the maximum distance, and if the grids are tilted the platens, and consequently the stock which they carry, will be brought together. It will be seen that by such an arrangement the load on the platens is a balanced load, that is to say, it will be the same on both sides of the grid pivots so that the operation of tilting the grids and therefore regulating the distance between the platens requires very little power and can be quickly accomplished.

The invention also contemplates using the grids in a horizontal position if desired in

which case the body of each grid is perpendicular to the platens as in the other example, and in any case the structure is very simple and the grids are made to operate as a unit.

In its simplest form the platens may be the actual pipes through which the heating medium is carried and thus directly applied to the stock or, for certain purposes, the pipes of the platens can carry plates on which the stock is piled. In any case the structure can be housed and used like most driers except that it can be handled with greater facility and at less cost.

Reference is to be had to the accompanying drawings forming a part of this specification in which similar reference characters refer to similar parts throughout the several views.

Figure 1 is a side elevation of the drier embodying my invention showing the grids in normal or open position;

Figure 2 is a broken side elevation showing the grids tilted to close the platens;

Figure 3 is an end view of the structure;

Figure 4 is a broken detail sectional elevation showing the position of the platens and stock when the platens are open;

Figure 5 is a similar view with the grids tilted to close the platens upon the stock;

Figure 6 is a side elevation of a drier showing a slightly modified arrangement of the platens and their supports;

Figure 7 is a broken plan view of the structure shown in Figure 6;

Figure 8 is a detail sectional view showing a type of platen adapted for use in the drier;

Figure 9 is a plan view of the modification in which the grids open laterally instead of vertically;

Figure 10 is a side elevation of the structure shown in Figure 9;

Figure 11 is a broken end view of the structure shown in Figure 10 but with the stanchions removed for clearness.

In carrying out the invention I use side supporting frames 10 which can be of any approved design and these carry a series of vertical grids having stanchions 11 which may be hollow to receive a heating medium and each of which is pivoted as shown at 11' 160

on the frame 10. The heating medium, which can be steam, water, oil, or other medium, is received through a header 12 at the upper part of the apparatus (see Fig. 1) and this connects by flexible pipes 13 with the several stanchions 11 which, as shown in Figure 3, are on opposite sides of the apparatus and form supports for the platens hereinafter referred to.

10 The header 12 is connected by flexible or jointed pipes 14 to a source of heat supply and on the lower side of the apparatus the several stanchions connect by flexible pipes 16 with a header 17 connecting through flexible or jointed pipes 18 with a suitable exhaust. Guide links 19 connect the upper and lower parts of the grids, to wit, the tie bars 20 which are attached to them, to the headers 12 and 17. The tie bars are by way of example and simply show one means of connecting the several stanchions 11 of the grids so that all may operate as a unit, and any suitable means can be used for tilting these grids but a simple and preferred means is illustrated in which the tie bars at the upper and lower parts of the grids connect by a cable 21 which runs over a sheave 22 on a shaft 23, and this can be turned by any reversible means and can conveniently be connected by a worm and gear structure 24 with a reversible motor 25.

15 The stanchions 11 of each grid are connected by cross pipes 26 or 27 as the case may be so that the circulation of the heating medium is through the stanchions and the cross pipes shown in Figs. 4 and 5 which are thus directly heated and which in the figures referred to serve as platens. For some purposes it is better to have the alternate grids provided with pipes of different sizes as shown in Figures 4 and 5. As here illustrated, it will be seen that the pipes 26 on two of the grid members are relatively large while the pipes 27 on the intervening grid members are smaller, thus a strip of stock 28 when arranged between the members will bear direct upon the pipes 26, but will be spaced from the pipes 27 thus providing better circulation of air between the stock parts.

20 From the description given it will be seen that the load, that is the stock 28, carried by the several grid members is a balanced load and it will bear upon opposite sides of the pivots 11' of the grids so that the only power necessary to tilt the grids is sufficient to overcome the friction of the load, and that the load does not need to be lifted and therefore the simple means shown serves as a quick and efficient way of affecting the opening and closing of the platens. For instance, when the grids are vertical, as in Figures 1 and 4, the platens will be open so that stock can be readily placed between them, and 25 when the grids are tilted the vertical dis-

tance will be changed so that the platen members will bear directly upon the stock and hold it flat. It will be understood too that the structure can be housed in any usual or preferred way, or any preferred means used 70 for circulating air and removing vapor in, through and from the apparatus.

25 In Figures 6 and 7 I have shown a slightly modified arrangement of the parts which, however, embodies no change in principle and here the several stanchions 11 are connected on opposite sides by I-beams 28' which act as a frame and which are pivoted as shown at 29 to the several stanchions. The I-beams on opposite sides can be held together by tie bars 30 as shown in Figure 8. In this style of the apparatus the several I-beams carry the pipe coils 31 through which the heating medium passes and the coils are at one end of the apparatus connected to a header 32 by a pipe 34 and with the source of supply of the heating medium by jointed pipes 32', while at the other end the exhaust header 33 connects by a pipe 35 with the coils and by jointed pipes 33' with the exhaust. I have not referred specifically to the jointed pipes as anyone skilled in the art will understand the making of the joints so as to permit the movement of the several parts connected therewith.

30 In this example of the apparatus the several pipe members 31, instead of acting as platens and also as heating mediums, are separated from the lumber or stock by perforated plates 36 and 36' each plate having circulation holes 37 therethrough (see Figure 8). The plates 36 and 36' are spaced from the pipe members by spacing blocks 38 and the lower plate 36' can be carried by the I-beams 28' while the upper plates can rest directly upon the spacing blocks. For some purposes, and especially where the nature of the stock is such that it is better to have it held out of direct contact with the pipes, this form of platen is better but the principle is exactly the same, and it will be seen by reference to Figures 6 and 7 that when the stanchions 11 are tilted or rocked, the operation will serve to open and close the platens precisely as already described. Although the cables 21 are connected to the upper and lower parts of the stanchions direct, if one stanchion is tilted the others must of necessity be, thus the several I-beams 28' serve as important links between the several stanchions so that when a stanchion is tilted the whole bank of grids is moved to bring the platens closer together or further apart as desired.

35 In Figures 9 to 11 I have shown another example of the organization of the apparatus in which however, the same principle of tilting grids obtains. As here illustrated, the grids are vertically instead of horizontally arranged and boards or the like can be placed between them. The grid stanchions 39 have 40

coils 40 like the coils 31 above referred to, and the coils connect at the upper ends through flexible pipes 41 with headers 42 which have a jointed pipe connection 43 with the source of heat supply, while at the lower ends the coils connect by flexible pipes 44 with headers 45 which connect through jointed pipes 46 with the exhaust. In the example given the coils are covered by perforated plates 47 or the plates 36 and 36' above referred to. At their upper and lower parts and on both sides of the apparatus the several stanchions 39 are pivoted to channel beams 48 which serve as a frame and these are pivoted as shown at 49 to the supports 50. An operating shaft 51 is located above the apparatus instead of at the end and cables 52 connect over sheaves 53 on the shaft with opposite ends of the upper frame members 48. 20 The shaft 51 can be turned by the worm gear and motor construction already referred to, or by other means. In any event when the upper frame members 48 are tilted the stanchions 39 serve as links connecting with 25 and spaced by the lower frame members and so the whole bank of grids tilt as a unit to open or to close the platens for the reception or removal of the stock.

In each of the examples given it will be noticed that the construction involves the use of tilttable grids acting as a unit in which the platens are opened and closed by the tilting of the grids so that the operation of the apparatus is exceedingly simple, very convenient, and requires little power. It will also be apparent that any customary or preferred means of regulating temperatures and circulation can be applied to this apparatus as to the more conventional types.

40 It will be noticed that in Figures 6 and 7 and also in Figures 9 to 11, a common principle is involved of using separable platens carried by grid structures all controlled by the tilting of the stanchions which carry the grids 45 or by the grids themselves, and this general feature is capable of many other structural arrangements without departing from the essential nature of the invention.

What I claim is:

- 50 1. A drier of the kind described comprising tilting grids having side members and connecting cross members, the cross members of which are adapted to carry a heating medium and which serve as stock platens.
- 55 2. A drier of the kind described comprising a bank of tilting grids operable as a unit, each grid having side members and connecting cross members, the cross members of each 60 grid acting to carry a heating medium and to serve as a stock platen.
- 65 3. A drier of the kind described comprising a bank of tilting grids each comprising a pair of stanchions connected by cross members, and means for carrying a heating me-

dium through the stanchions and the cross members.

4. A drier of the kind described comprising tilting grids connected to operate as a unit, each grid having cross members to carry a heating medium and act as stock platens with the cross members of some of the grids of a different diameter than those of the remaining grids.

5. A structure of the kind described comprising a series of tilting grids, each grid having side stanchions and cross members connecting the stanchions and arranged to carry a heating medium, and a connection between the several grids by which they tilt as a unit.

6. A drier comprising a plurality of tilting stanchions, frame members pivotally connecting the several stanchions whereby they tilt as a unit, and platens carried by the frame members.

7. A drier comprising a plurality of tilting stanchions connected to tilt as a unit, cross circulation pipes carried by the stanchions and serving as platen heaters, and perforated plates over the circulation pipes.

8. A drier comprising a series of tilting stanchions arranged in opposed pairs and separable platens carried by and connected to each pair of stanchions whereby the tilting of the stanchions regulates the separation of the platens.

9. A drier comprising a series of separable grids having opposed side members and connecting cross platen members, platen heating elements carried by the grids, and a connection between the grids and stanchions whereby the tilting of the stanchions controls the separation of the whole series of grids.

10. A drier of the kind described comprising a series of parallel grids each having opposed side members and connecting cross platen members, and a connection between the several grids whereby they all operate as a unit and by their tilting action act to regulate the separation of the platens.

In testimony whereof, I have signed my name to this specification this 12th day of April, 1929.

BURT S. HARRISON.
